US0D1107703S

(12) **United States Design Patent** (10) **Patent No.:** **US D1,107,703 S**
(45) **Date of Patent:** **** Dec. 30, 2025**

(54) **READER DEVICE**

(71) Applicant: **Stripe, Inc.**, South San Francisco, CA (US)

(72) Inventors: **James Foody**, Clinton, NY (US); **Conor Hayes**, County Westmeath (IE)

(73) Assignee: **Stripe, Inc.**, South San Francisco, CA (US)

(**) Term: **15 Years**

(21) Appl. No.: **29/835,571**

(22) Filed: **Apr. 20, 2022**

(51) **LOC (15) Cl.** **14-02**

(52) **U.S. Cl.**

USPC **D14/385**
